UNITED STATES PATENT OFFICE.

HARRY L. DAUGHERTY, OF CARSON CITY, NEVADA.

BIT.

1,384,242.

Specification of Letters Patent. Patented July 12, 1921.

Application filed February 17, 1920. Serial No. 359,371.

To all whom it may concern:

Be it known that I, HARRY L. DAUGHERTY, a citizen of the United States, and a resident of Carson City, in the county of 5 Ormsby and State of Nevada, have invented certain new and useful Improvements in Bits, of which the following is a specification.

My invention is an improvement in bits, 10 and has for its object to provide a bit especially adapted for riding bridles, and wherein a bit bar is provided with a curb, and cheek pieces in the form of plates extending above and below the bit bar, each 15 piece having an opening at its top, and a tongue hinged to move transversely of the opening to form with the cheek piece a buckle, each cheek piece having a rosette forming a keeper below the opening.

20 In the drawings:—

Figure 1 is a perspective view of the improved bit.

Fig. 2 is an enlarged section on the line 2—2 of Fig. 1.

25 In the present embodiment of the invention the improved bit comprises cheek plates 1, which are shaped like the lower leg, being arranged with the foot portion downward and the broadest portion of the cheek pieces 30 are connected by a bit bar 2, which is provided intermediate its ends and at its center with a laterally offset portion 3 forming a curb. The foot portions of the cheek pieces are connected by a cross bar 4, the said cross 35 bar being a strip of metal having its ends bent laterally as indicated at 5, and secured to cheek pieces in any suitable or desired manner.

40 On the outer face of each cheek piece and at the end of the bit bar, there is a rosette 6, the rosettes being formed in the present instance by hollow spherical segments which have their edges abutted against the cheek pieces and secured thereto in any suitable

manner as for instance by brazing or soldering. 45

At its top and bottom the edges of the rosette are cut away as shown at 7 for a purpose to be presently described, and each cheek piece has at its top a circular opening 8 extending transversely of the cheek piece. A tongue 9 is pivoted at its opening to extend diametrically thereof, on the outer face of the cheek piece. Each tongue has an eye 10, which is bent through an opening 11 in the 55 cheek piece below the opening 8, the arrangement being such that the tongue will freely swing toward the rosette.

The cheek strap of the bridle 12 passes through this circular opening 8, and through 60 the notches or recesses 7 in the rosette forming a keeper for the end of the strap, and the said strap has openings 13 arranged in a series extending longitudinally thereof, for engagement by the tongue 65 the cheek pieces and the tongue co-operating to provide a buckle.

I claim:—

A bit comprising flat longitudinal curved cheek plates having their intermediate portions enlarged laterally, a bit bar connected to the enlarged intermediate portions of said flat cheek plates, the upper portions of said plates having strap receiving openings, strap fastening tongues contacting with the outer 70 sides of said flat plates above said openings and having loops passed through said plates beneath said openings, and sphere shaped rosettes attached to the outer sides of said plates at the ends of said bit bar and having 75 spaced upper and lower aligned strap receiving openings defining spaced keeper means for the straps, said rosettes being directly beneath said strap receiving openings and of a diameter less than the width of the 80 enlarged intermediate portions of said cheek plates. 85

HARRY L. DAUGHERTY.
